UNITED STATES PATENT OFFICE.

HENRY RICHARDSON, OF CHICAGO, ILLINOIS, AND WILLIAM LIPPERT, OF KENOSHA, WISCONSIN; SAID LIPPERT ASSIGNOR TO SAID RICHARDSON.

WIRE FABRIC.

1,261,293.

Specification of Letters Patent.

Patented Apr. 2, 1918.

Application filed August 3, 1914. Serial No. 854,650.

To all whom it may concern:

Be it known that we, HENRY RICHARDSON, a subject of the King of Great Britain, residing at Chicago, in the county of Cook and 5 State of Illinois, and WILLIAM LIPPERT, a citizen of the United States, residing at Kenosha, in the county of Kenosha and State of Wisconsin, have invented certain new and useful Improvements in Wire Fabrics, of 10 which the following is a specification.

This invention relates to improvements in wire link fabrics of that type extensively used to form bed and couch bottoms, and pertains more particularly to a type of such 15 fabrics which are made of comparatively light wire and wherein the links or units are so formed and connected as to present a high degree of tensional strength, especially in the line of longitudinal strain.

20 The general object of the invention is to provide an improved, simple and strong link fabric of the light wire type, employing a minimum amount of wire in its manufacture, and readily lending itself to manufacture by 25 comparatively simple and easily performed machine operations.

The bent wire link forming the basis of the present fabric is made of a single piece of wire, the intermediate portion of which is 30 bent or folded upon itself, thus forming a two-ply body member with a looped end, and the end portions of the wire are preferably extended downwardly at the other end of the link to an extent sufficiently to form 35 substantially vertical shoulders or offsets, and are thence directly extended laterally of the body member, one of said end portions forming a cross-arm for connection to an adjacent strand of the fabric and the other end portion being preferably secured to some part 40 or element of the link itself. In some of the forms which we have selected for illustration, the link also includes a lateral eye on the opposite side of the body member from the cross-arm, which lateral eye is formed 45 as a direct angular extension of one of the shouldered or offset portions. The cross-arm and the lateral eye may both be formed from one of the end portions of the wire, or they 50 may be formed from the two end portions of the wire, respectively. An additional feature of improvement resides in a novel form of terminal hook for the free end of the cross-arm; such hook being formed with a 55 substantially vertical shoulder or offset at

the base of the hook which bears upon a lateral eye on a laterally adjacent link and cooperates with the hook proper in resisting the tensional strain on the cross-arm. The individual links are assembled end-to-end 60 to form the longitudinal strands of the fabric by a simple interengagement of the looped end of one link with the opposite end of the next adjacent link, and the terminal hooks or loops of the cross-arms are flexibly 65 engaged with the links of an adjacent strand.

In the accompanying drawings we have illustrated our invention in a variety of specifically different forms, all of which, however, embody the basic principle of the invention, and referring thereto—

Figures 1, 3, 5, 7, 9, 11 and 13 are fragmentary top plan views of several slightly varying forms of our fabric;

Figs. 2, 4 and 6 are perspective details, respectively, of portions of Figs. 1, 3 and 5;

Figs. 8, 10, 12 and 14 are perspective details, respectively, of portions of Figs. 7, 9, 11 and 13.

In all of the several embodiments of the 80 invention illustrated the link is formed of a single piece of wire having its intermediate portion bent or folded upon itself to provide a two-ply body or tension member 5 having a looped end 6 or 6' uniting the limbs of the 85 body member at that end of the link. Furthermore, in all of the forms illustrated excepting that of Figs. 5 and 6, the end portions of the wire at the other end of the body member 5 are downwardly bent to form 90 a pair of substantially vertical shoulders or offsets 7. In the form shown in Figs. 1 and 2, one end portion of the wire is extended laterally of the lower end of one of the offsets 7 to form a cross arm 8, while the 95 other end portion of the wire is similarly extended laterally from the lower end of the other offset 7 on the opposite side of the body member 5 and is bent to form a lateral eye 9, the wire being thence continued across the 100 body member 5 and its extreme end secured to the cross arm 8 as by a hook 10.

In the form illustrated in Figs. 3 and 4, the cross-arm 8 is formed the same as in Figs. 1 and 2, but the lateral eye 11 has its 105 free end secured to the body member 5 by a hook 12.

Figs. 5 and 6 illustrate merely a slight modification of Figs. 3 and 4, wherein the cross-arm 8' and lateral eye 11' extend sub- 110

stantially in the plane of the body member 5, and the opposite or looped end 6' of the link is formed with a downward offset for engagement with the inner ends of the cross-arm and lateral loop, respectively. It may here be noted that this modification can be carried out through all of the forms of the invention shown except that of Figs. 13 and 14, if desired, it being practically immaterial 10 so far as the results obtained are concerned at which end of the link the downward offset is formed.

It will be noted that in all of the forms thus far described, one end portion of the 15 wire is utilized to form the cross-arm and the other to form the secured lateral eye. A fabric having substantially the same structural characteristics can be formed by using one end portion only of the wire to 20 form both the cross-arm and the lateral eye, as illustrated in Figs. 7 to 12 inclusive. In the constructions of Figs. 7 and 8, and 9 and 10, one end portion of the wire is first extended laterally from the lower end of one 25 of the shoulders 7 and bent to form the lateral eye 13, the wire extending thence across the body member 5 to provide the cross-arm 14 as a continuation of one side of the lateral eye 13. The other end portion of the 30 wire is bent laterally from the lower end of the other shoulder 7, as shown at 15, and, as shown in Figs. 7 and 8, its extreme end is 35 formed into a hook 16 that engages the cross-arm 14. As shown in Figs. 9 and 10, the extreme end of this end portion of the wire is curled around the cross-arm 14 as shown at 17, this latter connection being somewhat stronger than the hook 16.

The structure of Figs. 11 and 12, differs 40 from that of Figs. 7 and 8 only in that the wire forming the lateral eye 13' is bent in the opposite direction, thereby throwing the lateral arm 14' beyond the shouldered end of the body member 5 and reversing the direction of the securing hook 16' relatively to the laterally bent portion 15' of the wire.

The construction illustrated in Figs. 13 and 14 omits the lateral eye. The cross-arm 8 is formed the same as in the structures of 50 Figs. 1 to 4 inclusive, while the other end portion of the wire is extended laterally from the lower end of the shoulder 7 beneath the inner end of the cross-arm 8, as shown at 18 in Fig. 14, and is thence carried 55 up and hooked or curled over the cross-arm as shown at 19.

In the constructions shown in Figs. 1 to 60 6 and 11 to 14 inclusive the outer end portion of the cross arm is carried through the lateral eye or around the body member of a laterally adjacent link and its extreme end is then brought up and hooked over the body of the cross-arm, thus forming a closed and secured loop 20. In Figs. 7 to 10 inclusive 65 we have illustrated a novel form of terminal

hook that can be used to advantage on either an integral cross-arm or a separate cross-link in connection with longitudinal links that are formed with a loop or eye extending laterally of the body or tension member. 70 This novel terminal hook resembles a plain ordinary hook, except that at the base of the hook the wire is bent upward at a rather steep angle to the body of the cross-arm or cross-link on which it is formed, thereby 75 forming a shoulder or hump 21 at the junction of the hook proper 22 with the member on which it is formed. This shoulder 21 engages and bears against the outer end of the lateral eye 13, while the hook proper 22 80 embraces and pulls against the body member 5. The tensional strain on the hook is thereby divided or distributed between the shoulder and the hook proper, thus greatly diminishing the liability of the hook to pull or straighten out under strain, and enabling a lighter gage of wire to be used than would be possible with the ordinary plain hook.

In all of the forms shown the links are 85 assembled endwise to form the longitudinal strands by a simple engagement of the looped ends 6 with the shoulders or offsets 7, or of the offset looped ends 6' (Figs. 5 and 6) 90 with the inner ends of the cross-arm 8' and lateral eye 11'. 95

We claim:

1. A wire link fabric comprising a plurality of links each consisting of a single piece of wire bent to form a two-ply tension portion, the plies of which both project laterally at one extremity of said tension portion, the projection of one of said plies being extended to form a cross arm, and one end of each link being provided with a vertically disposed offset or shoulder engaging the opposed end of an adjacent link whereby the links are longitudinally connected together, the cross arm of each link being connected to a laterally adjacent link. 100 105

2. A wire link fabric comprising a plurality of links each consisting of a single piece of wire bent to form a two-ply tension portion, the plies of which both project laterally at one extremity of said tension portion, the projection of one of said plies being extended to form a cross arm and the other projection being anchored to an element of the link, and one end of each link being provided with a vertically disposed offset or shoulder engaging the opposed end of an adjacent link whereby the links are longitudinally connected together, the cross arm of each link being connected to a laterally adjacent link. 110 115 120

3. A wire link fabric comprising a plurality of longitudinally connected links each consisting of a single piece of wire folded upon itself to form a two-ply tension portion, said plies at one extremity of the tension portion being bent to form a laterally 125 130

disposed eye and a transversely extending cross arm, the opposed end of a longitudinally adjacent link being connected to said tension portion so as to extend within the 5 perimeter of said laterally disposed eye and embrace both of the plies of said tension portion, the ends of said cross arms being connected to laterally adjacent links.

4. A wire link fabric comprising a plurality of links each consisting of a single piece of wire bent to form a two-ply tension portion, said plies at one extremity of said tension portion being bent vertically to form vertical offsets or shoulders and then 10 extended laterally in opposite directions, one of said extensions forming a cross arm and the end of the other extension being anchored to an element of the link, the ends of said cross arm being connected to laterally adjacent links.

5. A wire link fabric comprising a plurality of links each consisting of a single piece of wire doubled to form a two-ply tension portion, the plies at one end of said 15 tension portion being bent vertically and then separated and extended laterally at the end of said vertical bend to form a laterally disposed eye and a cross arm both disposed in a plane substantially parallel to 20 but not coincident with the horizontal plane of said tension portion, the free end of one of said lateral extensions being anchored to an element of the link, and the vertical bend of each link being engaged by the opposed 25 end of a longitudinally adjacent link whereby the links are connected longitudinally, and the ends of said cross arms being connected to laterally adjacent links.

6. A wire link fabric including a plurality of links, each formed of a single piece of wire, the intermediate portion of which is folded upon itself to form a two-ply body member with a looped end, and the end portions of which are extended downwardly at 30 the other end of the link to form substantially vertical shoulders or offsets and are thence directly extended laterally of the body member in opposite directions, one of said end portions being bent to form a lateral 35 eye on one side of said body member and a cross-arm connection on the other side of said body member to an adjacent strand of the fabric, and the other end portion having its free end secured to an element of the link; said links being assembled 40 with their shouldered and looped ends engaged with each other to form the longitudinal strands of the fabric and with the outer ends of their respective cross-arms engaged 45 with the lateral eyes of the links of an adjacent strand.

7. A wire link fabric including a plurality of bent wire links, each formed with

a body member and a lateral eye and connected end-to-end to form the longitudinal 65 strands of the fabric, and cross-connecting members between adjacent strands, each having a terminal hook engaged with the body member of a laterally adjacent link and a shoulder or hump on the base or inner end of said hook engaged with the eye 70 of said laterally adjacent link.

8. A wire link fabric including a plurality of links, each formed of a single piece of wire bent to provide a body member, a lateral eye on one side of said body member and a cross-arm on the other side of said body member having at its free end a hook formed with a shoulder or hump at its base or inner end; said links being connected 75 endwise to form the longitudinal strands of the fabric and with the hooks and shoulders of their respective cross-arms engaged with the body members and lateral eyes respectively of the links of an adjacent strand. 85

9. As a new article of manufacture, a wire fabric link formed of a single piece of wire intermediately bent to form a two-ply tension portion having its two plies united by cross connection at one end, said plies at 90 the other extremity of the tension portion being extended laterally to form a laterally disposed eye on one side of said link and a cross arm projecting transversely on the other side of the link, and one extremity of 95 said tension portion having a two-ply vertical offset or shoulder adapted to be engaged by the tension portion of a longitudinally adjacent link.

10. As a new article of manufacture, a wire fabric link formed of a single piece of wire doubled intermediately to provide a two-ply tension portion, the plies of which both project laterally at one extremity of the tension portion, and one of said projections being extended to form a transverse cross arm, one end of each link being provided with a vertically disposed offset or shoulder between the tension portion and the lateral projections, adapted to be engaged by the opposed end of a longitudinally adjacent link. 100

11. As a new article of manufacture, a wire fabric link formed of a single piece of wire bent to provide a body member, a lateral eye on one side of said body member, and a cross-arm on the other side of said body member having at its free end a hook formed with a shoulder or hump at its base or inner end. 115
